UNITED STATES PATENT OFFICE

THOMAS SCOTT GRIEVE, OF LEICESTER, ENGLAND

STOCKING KNITTING MACHINE AND METHOD

Application filed March 25, 1931, Serial No. 525,259, and in Great Britain April 5, 1930.

This invention relates to stockings and concerns a method of and machine for producing, in a continuous operation, a stocking with a plain leg and a ribbed top in which there are a greater number of loops in the courses than there are in the courses of the leg portion, the desideratum in stockings of this kind being to provide a wide ribbed top which will be elastic and also afford additional comfort in wear, and a good anchorage for the suspenders.

The leg and extra wide ribbed top are integral with each other, and knitted automatically on the same machine.

15 The invention comprises a method of knitting a seamless stocking having a plain knitted foot and leg and a wide ribbed top, and a circular knitting machine having two sets of needles for carrying said method into practice, features of which will be hereinafter described and set forth in the claims.

The machine is capable of operating at times with the necessary rotary reciprocating motion for the purpose of producing 25 seamless heel and toe pouches, and I may so arrange the carrier of the jack needles that it may be moved or displaced relatively to the other carrier so as to carry the jack needles away from the other needles to provide the necessary room for the formation of the heel and toe pouches and also for a splicing yarn to float across the needle circle.

It will be understood that when the jack needles are equal in number to the other needles, a 1/1 rib fabric will be produced when the two sets of needles co-operate. The invention is not, however, limited to the provision of any particular number or any particular proportion of needles. I may, for example, provide a complement of jack needles containing a less number of needles than those in the plain set.

It is the intention to make the machine so that it will operate in a fully automatic manner for producing the stocking commencing at the toe and terminating at the welt, such stocking consisting of a seamless plain leg and foot with a 1/1 or other ribbed top, and terminating welt, the necessary changes in 45 the machine being brought about automatically

and without the necessity of transfer-
ence of loops.

After the formation of the welt the top of the stocking may be finished off with a shogged or locking course in the usual manner, after which the loops are cast off the jack needles only between the welt and the toe of the next stocking, the jack needles being then put out of action so that knitting proceeds on the next stocking on the other needles, the 55 jack needles being re-introduced into action when the next ribbed top on the next stocking is to be formed.

I prefer to make the knitting machine with revolving needle carriers and stationary 65 cam systems, an advantage of this type of machine being that increased speed and more balanced movement can be obtained.

In order that the invention may be more clearly and readily understood, a practical 70 example of a machine constructed in accordance with the invention and a stocking such as may be produced thereon will be herein-
after described with reference to the accom-
panying drawings, wherein 75

Figure 1 is a front elevation of such ma-
chine.

Figure 2 is a left hand side elevation of
same.

Figure 3 is a sectional front elevation of 80
the top head shown in its normal position.

Figure 4 is a part sectional front eleva-
tion of said top head in a lower position
wherein the jack needles are in operative
relation with the cylinder needles. 85

Figure 5 is a sectional detail hereinafter referred to.

Figure 6 is a view similar to Figure 4 but showing a pressing off cam in operation. 90

Figure 7 is a sectional side elevation of
part of the top head showing a clearing cam
in operation.

Figure 8 is a sectional plan view of the ma-
chine taken on line VIII—VIII of Figure 1 95
i.e. with the top head removed.

Figure 9 is a sectional plan view of the
top head inverted, the section being taken
on line IX—IX of Figure 3.

Figure 10 is a sectional plan view, and 100

Figure 11 a side view of tapered high splicing mechanism hereinafter described.

Figure 12 shows a stocking such as may be produced on the machine illustrated.

5 According to the illustrative example of the invention I provide a circular knitting machine furnished with a top head which includes a rotary needle carrier 1 in the form of a sleeve for the jack needles 2. The carrier 1 has attached thereto, concentrically, a trussed ring 4 for guiding the shanks 3 of the jack needles during radial movement thereof and is driven synchronously with a needle cylinder 5 by means of an attached gear 10 wheel 6 and a pinion 7 on a shaft driven in a manner common to circular rib knitting machines of the superposed needle cylinder 15 type.

The carrier 1 is mounted to rotate on a concentric sleeve 8 furnished with a flange 9 by means of which it is fixed in the top plate 10 of the machine, and said carrier is supported, through the medium of the gear 6, and a ball bearing 11 in a cylindrical support 12 vertically movable in an opening 13 in the top plate 10.

The top head also includes a cam system for operating the jack needles, said system being carried partly by a sleeve 14 furnished 30 with lateral lugs 15 which rest on the upper end of the support 12, and partly by means of the support 12, as will be hereinafter set forth. The sleeve 14 serves as a bearing for a cam operating plunger 16. There is thus provided a top head which is both movable up and down in the machine and removable bodily from the machine for access to the component parts.

40 As shown in Figure 3 the top head normally occupies a raised position so as to provide room between the head and the needle cylinder 5 for the formation of heels and toes and is moved down to enable the jack needles to co-operate with the cylinder needles, when required, by pressure applied to the upper end of the sleeve 14, the lower position being shown in Figures 4, 6 and 7.

This pressure is applied by a lever 17 (see particularly Figures 1 and 2) pivotally mounted in a bracket 18 carried by the flange 9, said lever being operated by a push rod 19, levers 20, 21, another push rod 22, and a pivoted lever 23 from cams on the existing pattern drum 24 of the machine (see Figures 1 and 2).

60 The downward movement is effected against the action of springs 25 located between the flange 9 and hollow members or caps 26 fixed in the lugs 15, said springs acting to retain the jack needle carrier 1 in its normal raised or inoperative position.

As shown more particularly in Figure 9 the cam system in the top head includes a stitch cam 27 on a ring 28 suspended from 65 the support 12, and a clearing cam 29 piv-

totally mounted at 30 on a smaller ring 31 attached to the sleeve 14. The rings 28 and 31 are so arranged that a track 32 is formed between them in which the stems of the swing jacks 3 travel. A cam 33 is also pivotally mounted at 34 upon the ring 31 and co-operates with a cam 35 on the ring 28 to effect pressing off on the jack needles upon completion of the ribbed top of the stocking.

At the required time the clearing cam 29 is moved to the operative position, indicated in dot and dash lines, to cause the jack needles to clear and take yarn by means of a pin 36 on a radially movable slide 37 located in a slot 38 in the ring 31, and operated by a cam formation 39 on the aforesaid plunger 16, as shown in Figure 7. The cam 33 is also rendered operative, when required, by means of a pin 40 on a radially movable slide 41 located in a slot 42 in the ring 31, this slide being operated by another cam formation 43 on the plunger 16, as shown in Figure 6.

The plunger 16 is operated i. e. depressed to move the cams 29 or 33 outwards by a lever 44 pivotally mounted at 45 in a post 46 fixed in one of the lugs 15, said lever being actuated by a push rod 47 in turn operated by suitable cams on the pattern drum 24 through the medium of another push rod 48 and levers 49 and 50. The outward movement of the cams is effected against the action of a spring ring 3a which serves to hold the jack needles in a normally retracted position as shown in Figure 3.

The machine may be provided with a half-round splicing attachment which, as shown in Figures 1, 2 and 8, comprises a yarn finger 51 pivoted at 52 on a bracket 53 and having a tail 54 adapted to be engaged by a pivoted lever 55 connected by a pull rod 56 to a bell-crank lever 57 which is actuated in timed relation with the revolutions of the needle cylinder by a cam 58 on a drum or disc 59 carried by the main driving shaft 60 of the machine.

As indicated in Figure 8 the cam 58 causes the finger 51 to move from the position indicated in full lines—the feeding position—to that indicated in dotted lines, in which position the splicing yarn *a* is floated across the needle circle, as indicated in dotted lines, in the space provided between the cylinder 5 and the top head when the latter is raised as aforesaid. When, however, it is required to cease splicing, the finger 51 is moved out of action, i. e. to the position indicated in dot and dash lines whereby the splicing yarn is carried, as shown, into a yarn trapping and severing device generally indicated at 61, and actuated at the required times by a cam on the drum 24 through the medium of a push rod 62, lever 63 and link 64. The splicing finger is rendered inoperative as aforesaid by a cam 65 on the drum 24 acting through a push rod 66 upon an extension 67 of the lever 110

55. The two arms of the lever 57 may be jointed together at 57a so as to enable the upper arm to be moved laterally out of the path of the cam 58, e. g. by pattern controlled means of any ordinary form (not shown) when the splicing finger is rendered inoperative so as to eliminate wear and tear and also noise at this locality.

If desired, the splicing finger may be operated so as to feed yarn to different numbers of needles in different courses respectively to produce sectional spliced areas with non-parallel e. g. tapering sides such, for example, as tapered high spliced areas, and for this purpose an attachment as shown in Figures 10 and 11 may be employed. According to this arrangement a lever 68 is connected to or with the splicing finger actuating lever 55, said lever 68 being furnished with a nose 69 for engagement normally with half-round splicing cams 58a which are adjustably mounted on an arcuate carrier member 70 fixed on a shaft 71 driven through a clutch 72 by a train of gears 73, 74 and 75 from another shaft 76 driven through gears 77 and 78 from the main driving shaft 60. The shaft 76 is carried in a bracket 79 attached to a circular casing 80 in turn carried by a support 81 attached to the machine frame 82.

30 Keyed on to the shaft 71 is a member 83 upon which a pair of ratchet wheels 84, 85 are mounted in such a manner as to rotate with said member but also to be capable of independent rotation respectively in opposite directions against the action of some suitable form of friction means (not shown). The ratchet wheels are retained in position on the member 83 by a pair of discs 86 applied to said member and secured by screws 86a.

40 The member 83 is also provided with a radial slot 87 in which a slide 88 is adapted to be moved against the action of a spring 89 by a pattern-controlled cam piece 90 pivotally mounted upon the casing 80. The slide 45 88 carries two pairs of pawls 91, 92, 93 and 94, arranged so that the pawls 91, 92 engage the ratchet wheel 84, while the pawls 93, 94 engage the ratchet wheel 85.

50 It will be understood that during the rotary movement of the member 83 the slide 88 is moved inwards radially when desired by the cam 90 which action causes the pairs of pawls to engage and rotate the associated ratchet wheels.

55 The ratchet wheels 84 and 85 carry respectively sectional cams 95, 96 which, as the ratchet wheels are rotated in opposite directions by the associated pawls, vary the extent of the gap between the ends 58b and 58a of the two cams 58a and thus causes corresponding variations in the duration of the action of the splicing yarn finger in different courses.

Two pairs of pawls are provided so that 65 ratchet wheels having teeth of a comparative-

ly coarse pitch may be employed to impart to the cams 95 and 96 a movement equivalent to the pitch of the needles every time the slide 88 is operated so that the graduation of the spliced area may be to the extent of one needle wale on each side of said area in each of desired courses. Each pair of pawls is arranged so that one pawl is in advance of the other by half the pitch of the teeth and the stroke is such that the pawls act alternately so that each wheel is racked round to the extent of half a tooth for each movement of the slide 88. If desired, the cam piece 90 may be brought into action at every other revolution of the member 88 so that the width of the spliced area varies by a needle wale on each side in every other course, thus forming a comparatively long gradually tapered spliced area. Similarly the cam piece may be so controlled that stepped or other spliced areas may be produced.

As already alluded to herein the machine is intended to produce a stocking of the form represented diagrammatically in Figure 12, i. e. comprising a foot *a*, and leg portion *b* of plain fabric, and a ribbed top *c* which has a greater number of loops in the courses thereof than the number of loops in the courses of the leg portion *b*, so that as represented in Figure 12, the ribbed top is appreciably wider than the leg portion. 95

The operation of the machine in producing this article is as follows:—

Knitting is commenced at the toe *d* of the article and proceeds in the usual manner to form the foot *a*, heel *e* and leg portion *b*. If desired the toe *d*, foot bottom *f* and heel *e* may be spliced, and a high splice *g*, which may be of ordinary form or tapered, may be formed. During the knitting of the foot and leg portion the top head is maintained in the raised position so as to provide the necessary room for the formation of the heel and toe pouches and to allow the splicing yarn, when introduced, to float across the cylinder where not knitted, as already mentioned herein, and it will be understood that during the formation of the toe and heel the motion of the machine changes from rotary to rotary recipro-

catory motion. Upon completion of the ribbed top the top head is lowered automatically to the position shown in Figure 5, after which the plunger 16 is pushed down against the action of a spring 97 to bring the cam or projection 43 into engagement with the slide 41 to move the cam 33 outwards so that the jack needles are projected. When the machine is equipped with latch needles a brush 98 is situated at this point for action upon the needles to open the latches. The brush is mounted on a pivoted bell-crank lever 98a and is spring urged towards the needles, but is normally held clear of the needles by a collar 99 on the push rod 47. When said rod 47 is raised to actuate the

plunger rod 16 the brush is released so that it operates upon the jack needles as and for the purpose aforesaid.

The plunger 16 is then pushed down further to bring the cam face 39 into contact with the slide 37 whereby the cam 29 is projected as represented in Figure 7, to cause the jack needles to clear and take yarn, following which said needles are retracted by 10 the stitch cam 27 and consequently form loops.

Another brush 102 is provided adjacent to the knitting point to ensure that all of the jack needle latches are open when said needles 15 move outwards to take the yarn. This brush is suitably operated by connections from the drum 24.

As already mentioned herein, when the jack needles come into action the number of 20 needles knitting is augmented and consequently the number of loops produced in the courses is increased, thereby producing a ribbed top such as *c* of the desired elasticity and increased width.

25 A tricked disc 100 is mounted on the top head by means of a ball bearing 100a and a ring 100b attached to the lower end of the sleeve 14. The purpose of this disc is to provide a draw edge and knocking over edge for 30 the jack needles and, when a 1/1 ribbed top is being made, to hold down the forming fabric, instead of the usual sinkers or web holders 101 which, as will be understood, are rendered useless owing to the presence of the rib 35 needles directly above them. As shown particularly in Figure 5 the disc 100 is formed with tricks on its underside to accommodate the nibs of those sinkers which are retracted. The forming fabric passes down 40 between the disc and the nibs of the sinkers where the latter are projected.

After a rib bed top of desired length has been knitted the plunger 16 may be returned to the position shown in Figure 6, which action 45 causes the jack needles to move outwards to clear their loops whereafter they are retracted by the cam 35 and press off. Alternatively if it is desired to form a welt knitting may be suspended on the jack needles for a 50 few courses and then resumed following which a locking course may be knitted and then the jack needles may be caused to press off.

As will be readily understood the machine 55 hereinbefore described is fully automatic and thereby enables a stocking of the form described to be produced completely in one continuous operation without stopping the machine.

60 When a tapered high splice is to be formed the mechanism hereinbefore described for this purpose is of course put into operation on the completion of the heel and is operated so that the duration of action of the 65 splicing finger is decreased as knitting pro-

ceeds since the area is commenced at the widest point.

An important feature of the machine is that the jack needles, when brought into action, increase the number of needles knitting. For example, if there are two hundred needles in the set upon which the plain fabric is knitted, and there are two hundred jack needles, then, when the jack needles are brought into action for the purpose of cooperating with the other needles to make the ribbed top, the latter will be knitted upon four hundred needles, thereby obtaining the desired result in the stocking.

What I claim then is:—

1. A method of knitting a seamless stocking having a plain knitted foot and leg and a ribbed top, which consists in commencing at the toe, knitting the foot and leg of plain fabric and then knitting a ribbed top which has in the courses thereof a greater number of loops than the number of loops in the courses of the leg, the change from plain to rib knitting being effected without transference of loops.

2. A method of knitting on a circular knitting machine having two sets of needles a seamless stocking having a plain knitted foot and leg and a ribbed top, which consists in knitting the foot and leg of the article upon the needles of one set, and then introducing into action the needles of the other set and without transference of loops from the needles of one set to those of the other set knitting a ribbed top, the needles of the second set augmenting the number of needles previously in action so that the ribbed top has in its courses a greater number of loops than those in the courses of the plain fabric.

3. A method of knitting on a circular knitting machine having two sets of needles a seamless stocking having a plain knitted foot and leg and a ribbed top, which consists in knitting the foot and leg of the article upon the needles of one set, and then introducing into action the needles of the other set and without transference of loops from the needles of one set to those of the other set knitting a ribbed top, the needles of the second set augmenting the number of needles previously in action so that the ribbed top has in its courses a greater number of loops than those in the courses of the plain fabric, said method being carried out in one continuous operation and in an automatic manner.

4. A circular knitting machine for the production of a seamless hose having a plain knitted foot and leg and a ribbed top, comprising a needle cylinder, a set of independent needles in said cylinder for knitting first the foot and leg of the article, a top head removable bodily from the machine and including a set of independent needles which, following the knitting of the leg of the article, co-operate with and augment the num-

ber of needles in action to produce the ribbed top with more loops in the courses than there are in the plain courses, and a cam system for actuating the needles in the top head, means to move the top head in relation to the needle cylinder, and means to render the cam system operative and inoperative.

5. A circular knitting machine for the production of a seamless hose having a plain 10 knitted foot and leg and a ribbed top, comprising a needle cylinder, a set of independent needles in said cylinder for knitting first the foot and leg of the article, a top head removable bodily from the machine and including a set of radially swinging jack needles which, following the knitting of the leg of the article, co-operate with and augment the number of needles in action to produce the ribbed top with more loops in the courses 20 than there are in the plain courses, and a cam system for actuating the jack needles, means to move the top head in relation to the needle cylinder, and means to render the cam system operative and inoperative.

25 6. A circular knitting machine comprising a needle cylinder, a set of needles therein, a top head including a set of radially swinging jack needles, a carrier for the jack needles, a member for guiding the jack needles 30 during radial movement thereof, a vertically movable support for the aforesaid carrier, a cam system for actuating the jack needles incorporating a movable clearing cam and a movable press-off cam, and a slideable plunger 35 for moving said cams to an operative position and means for controlling said plunger automatically, for the purpose described.

7. A circular knitting machine comprising a needle cylinder, a set of needles therein, a 40 movable top head including a set of radially swinging jack needles, a carrier for the jack needles, a member for guiding the jack needles during radial movement thereof, a vertically movable support for the said carrier, 45 a cam system for actuating the jack needles incorporating a movable clearing cam and a movable press-off cam, and a slideable plunger for moving said cams to an operative position, means for controlling said plunger automatically, and means to move the top head 50 automatically in relation to the needle cylinder.

8. A circular knitting machine comprising a needle cylinder, a set of needles therein, 55 a movable top head removable bodily and including a set of radially swinging jack needles, a carrier for the jack needles, a member for guiding the jack needles during radial movement thereof, a vertically movable support for the said carrier, a cam system for 60 actuating the jack needles incorporating a movable clearing cam and a movable press-off cam, and a slideable plunger for moving said cams to an operative position, means 65 for controlling said plunger automatically,

and means to move the top head automatically in relation to the needle cylinder.

9. A circular knitting machine comprising a needle cylinder, a set of needles therein, a top head including a set of radially swinging jack needles, a carrier for the jack needles, a member for guiding the jack needles during radial movement thereof, a vertically movable support for the aforesaid carrier and a cam system for actuating the jack needles for knitting purposes, means to move the top head automatically in relation to the needle cylinder, and a draw edge and knocking over member for the jack needles, said member being adapted also to hold down the web and being carried up and down with the top head, for the purposes described.

10. A circular knitting machine comprising a needle cylinder, a set of needles therein, a top head including a set of radially swinging jack needles, a carrier for the jack needles, a member for guiding the jack needles during radial movement thereof, a vertically movable support for the aforesaid carrier and a cam system for actuating the jack needles for knitting purposes, means to move the top head automatically in relation to the needle cylinder, mechanism for effecting tapered splicing, which includes sectional cams (such as 95 and 96) mounted upon ratchet wheels (such as 84 and 85) adapted for rotation intermittently in opposite directions and in timed relation with the needle cylinder, and means for effecting the intermittent rotation of the cams.

In testimony whereof I affix my signature.
THOMAS SCOTT GRIEVE.
